Attorney.

UNITED STATES PATENT OFFICE.

EDWIN K. O'BRIEN, OF CHARLOTTESVILLE, VIRGINIA.

DEVICE FOR INSERTING EXPLOSIVE CHARGES IN EARTH.

1,247,567.

Specification of Letters Patent. Patented Nov. 20, 1917.

Application filed February 8, 1917. Serial No. 147,345.

To all whom it may concern:

Be it known that I, EDWIN K. O'BRIEN, a citizen of the United States, residing at Charlottesville, in the county of Albemarle 5 and State of Virginia, have invented certain new and useful Improvements in Devices for Inserting Explosive Charges in Earth, of which the following is a specification.

- 10 This invention relates to devices for inserting and exploding explosive charges in the earth, for the purpose of loosening and removing the earth by the action of the explosive, or for rendering the earth in condition 15 to be easily taken out, in order that cavities may be created in which to plant trees or the like, or for the erection of fence posts, or for the excavation of ditches for whatsoever use desired.
- 20 The object of this invention is the production of very simple, cheap and readily manipulated devices for the uses stated, and having parts of special construction and arrangement with relation to each other.
- 25 In the accompanying drawings there are illustrated the construction and arrangement of the parts as preferred in this invention, and Figure 1 represents a side view of the parts assembled before driving into 30 the earth. Fig. 2 is a like view with the nose or point of the drill started into the earth. Fig. 3 is a side view showing the casing after it has been driven into the earth and the drill withdrawn. Fig. 4 is a like 35 view showing the casing in the earth with the drill taken out and the cartridge in place upon the internal shoulder at the bottom of the casing. Fig. 5 is a side view showing the casing in the earth, the cartridge in place, and the drill raised into firing 40 position and the upper end of the drill supported above the upper end of the casing by the removable clip attached to the firing cord. Fig. 6 is a cross section upon 45 the broken line 6—6 of Fig. 5 showing the removable clip in place clasping the drill shank.

Throughout this description and drawings the same letter is used to refer to the 50 same part.

Considering the drawings, the drill A has the head *a* and point *B*. The head of the drill is of greater diameter than the interior of the casing C within which the drill is removably located as illustrated. The drill 55 is longer than the casing C. As usually con-

structed the casing C has a reinforce collar *c* at the top, and an internal shoulder *D* at the bottom.

In Fig. 1 the point of the drill within the 60 casing is shown at the ground line *b* ready to be driven into the earth. Fig. 2 shows the drill started into the earth, and the head *a* of the drill in contact with the collar *c* of the casing C. If the drill be now driven 65 farther into the earth the casing is carried with it. At any suitable depth such as is set out in Fig. 3, the drill may be removed and the casing C left in the earth. By reason of the fact that the drill is longer 70 than the casing, a cavity E is formed below the casing in the ground. Into the cavity E the cartridge *e* is placed, and, the internal shoulder *D* of the casing serves to center the cartridge, which is the function intended. 75

To avoid accidents the cartridge is fired from a distance, and the means for accomplishing the firing are set out in Figs. 5 and 6. A spring clip F, usually made of sheet metal, has an upwardly-extended finger or 80 projection *f*, and when the clip clasps the upper portion of the shank of the drill the finger *f* passes under the head *a*. The clip rests upon the collar *c* of the casing and, as the upper portion of the drill is thus supported above the upper end of the casing, the point *B* of the drill within the casing 85 is raised to a distance above the primer of the cartridge. The lanyard or firing cord G is secured to the clip F. 90

In the operation of this invention, the parts are first assembled and arranged as illustrated in Fig. 1. Then, the drill is driven into the earth until the head of the drill meets the collar or rim of the casing. 95 Further driving carries the casing down also. The drill is then withdrawn, and, as the drill is longer than the casing a cavity E is formed below the lower end of the casing. Into this cavity the cartridge is introduced, and the rim of the cartridge rests upon and the cartridge is centered by the internal shoulder *D* at the bottom of the casing. Next, the drill is introduced and the clip F placed upon the upper part of the 100 shank with the fingers *f* under the head of the drill. In that way the point of the drill within the casing is raised some distance above the primer of the cartridge. A pull upon the lanyard G from a distance drops 105 the drill upon the cartridge and the explosion takes place as will be readily under-

stood. Usually, the result is to form a much enlarged cavity at the bottom of the casing, and to fully loosen the earth about the casing, if the explosive is of the proper amount and strength. It is not intended to confine this invention to the employment of any particular kind of explosive, or to the size or form of the cartridge. It has been found in practice, when using this invention preparatory to setting out fruit trees, that by selecting the proper size cartridges, the earth is loosened sufficiently to permit the easy removal of the casing and drill, neither of which is blown out by the explosion, and to take out the earth to an extent ample for the purpose desired.

Having now described this invention, and explained the mode of its operation, what I claim is:—

- 20 1. In an explosive inserter and exploder, the combination with a casing, of a drill arranged movably within the casing and having greater length than the casing and a head greater in diameter than the interior 25 of the casing, the said casing having an internal shoulder at the bottom.
2. In an explosive inserter and exploder, the combination with a casing, the said cas-

ing having a reinforced rim, of a drill arranged movably within the casing and having greater length than the casing and a head greater in diameter than the interior of the said casing, the said casing having an internal shoulder at the bottom.

3. In an explosive inserter and exploder, 35 the combination with a casing, of a drill arranged removably within the casing and having greater length than the casing and a head greater in diameter than the interior of the said casing, and releasable means acting upon the casing and upon the drill to support the upper end of the drill above the casing.

4. In an explosive inserter and exploder, 45 the combination with a casing, of a drill arranged removably within the said casing and having greater length than the casing and a head greater in diameter than the interior of the said casing, releasable means acting upon the said drill and upon the said 50 casing to support the upper end of the drill above the casing, and devices acting upon the said drill-supporting means for releasing the same from a distance.

In testimony whereof I affix my signature. 55
EDWIN K. O'BRIEN.
